UNITED STATES PATENT OFFICE.

WILLIAM H. SHUTTE, OF EMPORIA, KANSAS.

MACHINE FOR FILING SAWS.

SPECIFICATION forming part of Letters Patent No. 251,959, dated January 3, 1882.

Application filed April 6, 1881. (Model.)

To all whom it may concern:

Be it known that I, WILLIAM H. SHUTTE, of Emporia, in the county of Lyon and State of Kansas, have invented a new and useful Improvement in Machines for Filing Saws, of which the following is a full, clear, and exact description.

The object of this invention is to provide a saw-filer better adapted to secure the accurate gaging of the depth of the saw-teeth, the equal action of the file on the saw-teeth throughout the whole length of the file, the automatic feeding of the file, and its adjustment for any desired angle or pitch of teeth.

The invention consists of a sliding carriage carrying a spring-and-pawl-actuated bent arm that serves as a gage for the depth of the saw-teeth, and at the same time to support the file-frame; and it consists, further, of an adjustable clamp secured on the bent arm for the direct support of the file-frame so constructed that the direction of the said frame and file can be changed vertically.

Figure 1 is a side elevation of the device, partly in section, in position on a saw-clamp. Fig. 2 is a front elevation of the same, partly in section, and with parts broken away to exhibit other parts. Fig. 3 is a sectional elevation of the file-frame-supporting clamp in position on line $z z$, Fig. 1. Fig. 4 is a sectional elevation on line $x x$, Fig. 2. Fig. 5 is a sectional elevation on line $y y$, Fig. 1. Fig. 6 is a plan of the file-frame-supporting clamp in position. Fig. 7 is a perspective view of the dog for regulating the feed of the file. Fig. 8 is a side elevation, indicating a circular or convex shaped saw held in a clamp to which the improved device may be applied.

Similar letters of reference indicate corresponding parts.

In the drawings, A represents a saw-clamp, consisting of two blocks held together by screws or other convenient devices in the usual manner, and holding between them a saw, B. On their outer faces these blocks are longitudinally grooved, as shown at b , for the reception of the lower edges of the guides c, that hold the carriage C, so that it will freely slide on the top of said clamp A.

The carriage C consists of two blocks, C' C², set on edge parallel with each other, and held

apart by smaller blocks d d. These parts of the carriage C are held together by screws or bolts f f, or other suitable device.

An arm, D, consisting of a stout rod having its ends bent down at right angles parallel with each other, is pivoted at its flattened extremity on a screw or pin, g, in the rear part of the carriage C, and extends out through an opening in the front of the carriage C, with its outer end screw-threaded and turned down within reach of the top of the clamp A. A set-screw, g', entered through the rear of the carriage C, can be turned against the said arm D, to adjust the screw-threaded end thereof relatively to the top of said clamp A.

A spring, D', fixed within the carriage C, is held against the inner bent end of the arm D by a screw or stud, g², and serves, under conditions hereinafter set forth, to restore said arm D to its normal position. On the other perpendicular end of the arm D is the clamping-block E, that holds the file-frame H, said arm D being entered down through a vertical mortise, h, in said block E, one side of which mortise h presents a central pivoting-point, i, by means of which the said block E is pivoted so as to be adjustable in a vertical plane, so that the file G may be inclined to any desired degree from the horizontal across the face of the saw. The set-screws k hold the block E on the arm D, and by setting up the one and loosening the other set-screw k the desired vertical inclination may be given to the file G.

As a means for gaging the pitch of the saw-teeth, a flanged plate, S, provided with radial graduations t, is slipped over the arm D upon the clamping-block E, and a mark, t', is made on the arm D to serve as a pointer, whereby the angle at which the file G is held across the saw B is indicated. On the plate S also are straight graduations u, and a corresponding pointer, v, is on the top of the block E, whereby the adjustment of the said block E in a vertical plane is indicated. The nut k' on the extremity of the arm D prevents the slipping down of the block E, and also serves to adjust and hold said block E at any desired height above the saw. The extremity of the arm D, coming in contact with the face of the clamp A, operates as a gage for the depth of the saw-teeth.

H represents the file-frame, consisting of a horizontal blade, H', having its lower edge convex, as shown at l, to correspond with the curve of the common three-cornered file G, 5 thereby making the under side of the blade H' and the lower edge of the file G parallel with each other, so that the said file G will cut the same depth at one as at the other end. A shank, H², is firmly welded or otherwise secured at right angles to the blade H', and through the lower end of said shank H², and parallel with the blade H', is passed a screw-bolt, l', having a handle, l², that is designed for tightening the file G in the said frame H. 10 In the inner end of the bolt l' is a hole, l³, for receiving the end of the file G. The other end of the file G is held in position by a dog, H³, that slips on the blade H', and is held and adjusted by a set-screw, m, by which the file G 15 can be adjusted or centered so as to make the bottom edge of said file G parallel with the bottom edge of the frame-blade H'. 20

Through the lower end of the dog H³ is a rod, m', having a handle, m², on the outer end 25 thereof, and the inner end of said rod m' has a flat projection, m³, against which the flat face of the file G lies, so that the latter may not turn, and has also a hole, m⁴, to receive the point of the file G. Said rod m' thus serves as a guide 30 for the position of the said file G. The rod m' is held in position in the dog H³ by a pin, m⁵, passed through said rod m against the inner face of the dog H³, and on the inner face of the dog H³ is a dial or indicator, I, to which the 35 pin m⁵ serves as a pointer, thus showing the operator the position or angle at which the operating-edge of the file G is placed. To turn the file G over the operator loosens the screw-bolt l' slightly, and then turns the handle m² 40 until the pin m⁵ indicates the right point on the indicator I.

The frame-blade H' has a space cut out, as shown at n, on its upper edge to facilitate the introduction of the frame H into and its removal from the clamping-block E, in whose longitudinal grooves k² it is held without taking said frame H apart. 45

Within the carriage C, near the front end thereof, is a ratchet attachment, M, consisting 50 of a segmental block, M', pivoted on a screw or stud, o, and provided with a row of holes,

o', set in a curved line corresponding with the curve of said block M'. A rod, M², has one end engaged in one of the holes o' and the other in a hole, p, in the inner perpendicular portion 55 of the arm D, and a reversible dog or pawl, M³, having slotted oppositely-turned ends q, swings loosely from a stud, q', in the lower end of the block M'.

When the saw-filer is in position, as shown 60 in Fig. 1, and file G is pressed down on the saw B, the dog or pawl M³ presses forward and forces the saw in position for filing the next tooth, and when the arm D is raised the pawl M³ is drawn back and engages with the next 65 tooth, and so on until each tooth is filed. The carriage C will be removed from the clamping-block A and replaced in a reverse position for filing the intermediate saw-teeth. The feed is regulated by changing the position of rod M² 70 in reference to the pivotal point o of block M', said feed increasing as the rod is moved nearer said pivotal point.

It will be seen that the outer extremity of the arm D, by resting on the face of the clamp 75 A, forms a most accurate gage for the depth of the saw-teeth, so that it is impossible to file one tooth deeper than another, and that the curve in the file-frame blade H' and the centering set-screw m enable the operator to apply the file with equal effect throughout its 80 whole length.

Having thus fully described my invention, what I claim as new, and desire to secure by Letters Patent, is—

1. The combination, with the clamp A and sliding carriage C, of the bent arm D, the block E, the block M', pivoted at o and provided with holes o', the rod M², and the pawl M³, substantially as described, whereby the feed is operated and graduated, as set forth. 85

2. In a saw-filer, the combination, with the pivoted arm D, of the file-frame-clamping block E, having vertical mortise h, provided with pivoting-point i, grooves k², and set-screws 90 k, substantially as herein shown, and for the purposes set forth.

WILLIAM HENRY SHUTTE.
